VINE SUPPORTING DEVICE

Filed April 26, 1930

FIG. I.

FIG. II.

FIG. III.

INVENTOR.

C. E. ROBBINS

BY *Victor J. Evans*
ATTORNEY

UNITED STATES PATENT OFFICE

CHARLES E. ROBBINS, OF SANTA CRUZ, CALIFORNIA

VINE SUPPORTING DEVICE

Application filed April 26, 1930. Serial No. 447,703.

This invention relates to improvements in holding devices and has particular reference to means for holding vines, branches of bushes and the like.

5 The principal object of this invention is to produce a device which may be attached to any suitable support for the purpose of quickly engaging the stems or stalks of growing vegetation.

10 A further object is to produce a device wherein the stalks so engaged may be quickly disengaged if desired.

A further object is to produce a device which is economical to manufacture.

15 A still further object is to produce a device which is neat in appearance and one which will not detract from any object to which it is secured.

20 Other objects and advantages will be apparent during the course of the following description.

In the accompanying drawings forming a part of this specification and in which like numerals are employed to designate like parts throughout the same,

25 Figure I is a top plan view of my device as the same would appear when attached to a fence or wall.

Figure II is a side elevation of Figure I, and

30 Figure III is a fragmentary detail view on an enlarged scale showing the device attached to a wire support such as a wire fence.

35 It has been common practice to secure branches of vines or bushes to various supports through the medium of staples, clips, string, screening and the like over which branches were entwined. Applicant has devised a very simple holding means for branches or vines which may be quickly attached to any suitable support after which vines or branches are engaged therewith and removably held by a sliding locking bar.

40 In the accompanying drawings wherein for the purpose of illustration is shown a preferred embodiment of my invention, the numeral 5 designates a support which may be a fence, wall or any other surface to which my device is attached. My device

45 consists of a wire or rod bent so as to form outstanding loops as shown at 6, which loops are connected by bridge portions 7. The bridge portions on the opposite side of each loop are staggered as best illustrated in Figure II. The end of the wire is preferably bent as shown at 8. At 9 I have shown a locking wire having a bent end 11. The result of this construction is that the member having the loops thereon is stapled or otherwise secured to the support 5 after which the various branches to be held are positioned between the respective loops and the locking wire 9 fed therethrough so as to retain the branches as illustrated in Figures I and II.

55 When it is desired to employ the same for supporting vines upon a wire fence the same is used as illustrated in Figure III, the strands of the fence being shown at 12. It is 60 obvious that my device may be attached to an arch or circular column by merely bending both parts thereof to conform to the contour of the arch or column.

65 It is to be understood that the form of my invention herewith shown and described is to be taken as a preferred example of the same and that various changes relative to the material, size, shape and arrangement of parts may be resorted to without departing from the spirit of the invention or the scope of the subjoined claims.

70 Having thus described my invention, I claim:

75 1. In a vine support of the character described, a wire adapted to be bent upon itself so as to form substantially semi-circular loops at intervals throughout its length, said loops being joined by bridge portions, and a locking wire adapted to be passed 80 through said loops for the purpose specified.

85 2. In a vine support of the character described, a bent wire formed so as to provide 90 spaced substantially semi-circular loops, the portion of wire between said loops forming bridge portions, the alternate bridge portions being staggered, and a locking wire 95 adapted to pass through said loops for the purpose specified.

3. In a vine support of the character described, a wire bent so as to form a substantially semi-circular loop, thence bent at right angles to said loop, thence bent again at 5 right angles to said last mentioned portion so as to form a second substantially semi-circular loop, thence bent again at right angles to said loop, thence bent again at right angles to said last mentioned portion to form 10 a third substantially semi-circular loop, the portion of said wire between the adjacent loops being staggered with relation to a vertical line passing through said loops and a locking wire adapted to pass through said 15 loops whereby the connecting portion between said loops and said locking wire forms a retaining means for vine branches.

In testimony whereof I affix my signature.

CHARLES E. ROBBINS.
